D. W. BARTRAN

HOE

Filed Oct. 10, 1923

UNITED STATES PATENT OFFICE.

DAVID W. BARTRAN, OF LAUREL, MISSISSIPPI.

HOE.

Application filed October 10, 1923. Serial No. 667,705.

To all whom it may concern:

Be it known that I, DAVID W. BARTRAN, a citizen of the United States, residing at Laurel, in the county of Jones and State 5 of Mississippi, have invented certain new and useful Improvements in Hoes, of which the following is a specification, reference being had therein to the accompanying drawings.

10 This invention relates to improvements in hoes and the object of the invention is the construction of a simple and efficient hoe by a novel method, employing the use of part waste material so as to minimize the expense of manufacture.

15 Another object of the invention is the construction of a hoe employing a peculiarly-constructed brace, and assembling the parts in the manner which results in a 20 strong and durable implement.

25 With the foregoing and other objects in view, my invention comprises certain novel combinations, constructions and arrangements of parts as will be hereinafter described, illustrated in the accompanying drawings, and more particularly pointed out in the appended claims.

In the drawings:

30 Figure 1 is a perspective view of a hoe constructed in accordance with the present invention, the handle therefor being indicated by dotted lines.

35 Figure 2 is a perspective view of the blade.

Figure 3 is a vertical, central, sectional view of the hoe.

Figure 4 is a perspective view of the tubing of the hoe.

Figure 5 shows the blank from which the 40 brace is formed.

Figure 6 is a sectional view, taken on line 6—6, Fig. 1.

45 Referring to the drawings by numerals, 1 designates the blade of the hoe, which I preferably form out of discarded band and circular saw steel, after saws are worn down to certain sizes or are broken, whereby said saws become useless for the work they are intended for. I cut a pocket 2 in the upper 50 edge of blade 1 for receiving the tubing 3. This tubing 3 is cut from stock and is comparatively inexpensive to produce. I can

form the tubing 3 of any size desired and then cut the blank (see Fig. 5) for the brace 4. This brace 4 is substantially triangular shape, in its blank form. I bend or form the blank into substantially a V-shaped structure, in cross section, as clearly indicated by dotted lines in Fig. 5 and the sectional view in Fig. 6; this angle brace 4, by reason of its V-shaped structure, naturally fits around the rounded surface of the tubing 3 (Fig. 1), forming an efficient brace for the tubing and the blade.

I slightly extend the outer lower edge of 65 the tubing (as at A, Fig. 3) beyond the outer face of the blade 1, the blade performing the function of a yoke, whereby a very strong positioning of the parts is obtained.

As I assemble the parts, I weld the same 70 together. At the present time I preferably use electricity for the welding.

I have found from practical experience that my method and product are very efficient from the standpoint of manufacture, 75 as well as practical use in the field.

The handle 6 (dotted lines) is adapted to be inserted in the tubing 3.

While I have described the preferred embodiment of my invention, and have illustrated the same in the accompanying drawings, certain minor changes or alterations may appear to one skilled in the art to which this invention relates, during the extensive manufacture of the same and I, 85 therefore, reserve the right to make such alterations or changes as shall fairly fall within the scope of the appended claims.

What I claim is:

A hoe comprising a blade provided with 90 a recess in its upper edge intermediate its width, a short length of tubing having one end portion resting in said recess, said tubing extending rearwardly from the blade, and a triangular brace arcuate in cross section disposed between and engaging the rear 95 face of said blade and the under portion of the rear end of said tubing, the tubing, blade and brace being secured together at their points of contact.

In testimony whereof I hereunto affix my signature.

DAVID W. BARTRAN.
